HORACE E. WOOLERY, OF ST. PAUL, MINNESOTA, ASSIGNOR TO WOOLERY MACHINE COMPANY, OF MINNEAPOLIS, MINNESOTA, A CORPORATION OF MINNESOTA

RAILWAY BOLT TIGHTENER

Application filed January 30, 1929. Serial No. 336,296.

This invention relates to bolt tighteners for railway rails, and the primary object is to provide a portable, power operated machine that can be quickly and easily mounted on and dismounted from the rails, and which can readily be moved longitudinally on the rails so as to be successively shiftable from one rail joint to another where it is to be stationed for operation upon the bolts and nuts which secure the connecting or tie plates to the adjoining rail ends. A further object is to provide a machine of a novel, efficient, and practical nature, for selectively tightening the nut on the bolt or releasing it therefrom, and which machine is so constructed that it will readily adjust itself to its work regardless of which side of the rail the head or nut ends of the bolt may project. A further object is to provide a bolt tightener in which the tightening pressure will be automatically released when it reaches a predetermined degree, so as to insure a uniform holding pressure by each bolt, and so as to prevent an overstrain on and weakening of the bolt by too great a pressure, but in which machine the operator may effect an adjustment to eliminate the automatic pressure release and provide a positive power drive which may be employed to advantage where, for instance, it is desired to twist off a bolt that has become rusted or "frozen", or which for some other reason cannot be removed or adequately tightened. A further object is to provide an improved and novel construction of wrench and supporting and driving mechanism therefor. A further object is to provide a novel and efficient power transmitting mechanism, including speed clutches and drives, for conveying and regulating motive power from an engine, at one end of the machine, to the tool or wrench holders that are preferably arranged at or near the other end of the machine. Further and more specific objects will be disclosed in the course of the following specification, reference being had to the accompanying drawings, wherein:

Fig. 1 is a side elevation of the machine, as seen from the right, as lowered to its operative position with respect to the rail.

Fig. 2 is a rear view of the machine as seen in Fig. 1.

Fig. 3 is a top or plan view of the machine and the rails and ties upon which it is carried, portions being broken away.

Fig. 4 is a side elevation similar to Fig. 1 but showing the machine in the raised position to which it is adjusted when moved from one location to another.

Fig. 5 is an enlarged sectional elevation as seen substantially as on the irregular line 5—5 in Fig. 1.

Fig. 6 is a sectional elevation on the line 6—6 in Fig. 5.

Fig. 7 is a sectional elevation on the line 7—7 in Fig. 5.

Fig. 8 is an enlarged detail plan view of the rear end of the machine, with various parts broken away and others in section, for purpose of illustration.

Fig. 9 is a sectional elevation as on the irregular line 9—9 in Fig. 8.

Fig. 10 is an enlarged sectional plan view on the line 10—10 in Fig. 1.

Fig. 11 is a sectional elevation on the line 11—11 in Fig. 10.

Fig. 12 is an end elevation of a power transmission housing and a certain control mechanism, as on the line 12—12 in Fig. 10.

Fig. 13 is an enlarged detail plan view, partly in section, of the speed clutches and the automatic pressure release, slip clutch associated therewith.

Fig. 14 is a sectional elevation of the automatic pressure release mechanism, as on the line 14—14 in Fig. 13.

Fig. 15 is a sectional elevation on the line 15—15 in Fig. 14.

Fig. 16 is a sectional elevation on the line 16—16 in Fig. 14.

Fig. 17 is a sectional elevation on the line 17—17 in Fig. 14.

Referring to the drawings more particularly and by reference characters, A and B designate a pair of railway rails that are secured to ties C, by spikes D, in the usual manner. The ends of adjoining rails are connected by laterally arranged tie plates E, secured by bolts F, that are usually alternately reversed, end for end. The bolts 100

customarily employed for this purpose have rounded heads, and adjacent the heads are provided with enlarged shank portions F^1 , which are preferably elliptical in cross section (see Figs. 8 and 9), and fit into similarly shaped holes in the adjacent tie plates, so that the bolts will not turn with the nuts when the latter are turned into place. The bolts must of course be held in place, by pressure upon the head ends, while the nuts, F^2 , are being secured, so that the non-circular portions F^1 will not become dislodged, and to this end, it may here be noted, I have provided means, as will presently be described, for so retaining the bolts in place during the tightening operation.

The main frame of my machine consists of a pair of laterally disposed, longitudinally extending, angle iron beams 20 connected by various parts of the machine, particularly including the engine base 21, cross bars 22, and a gear and shaft housing 23, (Figs. 5 and 10). A tubular shaft or pipe 24 is attached, transversely, to the front ends of the beams 20, and between the beams is provided with a flanged roller 25 which supports the front end of the machine upon the rail A.

The machine is almost entirely supported by the rail (A) on which it is working, and must of course be retained in an upright position at such times, and consequently I give it lateral support from the opposite rail, B, by providing a frame 26 having a roller 27 for travelling contact with the rail B. This frame 26 is readily detachable with respect to the main frame and preferably comprises a bar 28, receivable in the pipe 24, and an angular brace 29 that may be secured in any desirable manner further back on the main frame.

By reference to Figs. 2 and 3 it will be noted that the machine is so designed that its weight while primarily carried on the rail A, is slightly overbalanced in the direction of the rail B so that the stability of the machine will be insured, and yet the weight is so distributed that it is a simple matter to quickly tumble the entire machine over, as indicated by dotted lines in Fig. 2, to manually remove it from the tracks, as becomes necessary when clearance must be given for an approaching train. To protect the machine from injury, when it is so tumbled over, I provide a pair of rockers 30, one at each end of the main frame, which support the machine when it is toppled over.

At what may for convenience be considered the rear end of the machine, the main frame is supported on a roller 31, that is slidably and rotatably carried on a shaft 32 secured in the rearwardly projecting arms 33 of a frame G that is pivotally connected to the main frame 20, as at 34. The frame G has an integrally cast, arched cross bar 35 with which is formed a bearing hub 36, the construction and func-

tions of which will presently be set forth. It may here be noted, however, that when the frame G is raised, or tilted up as shown in Fig. 4, it raises the entire rear end of the machine, so that it may be moved from one rail joint to another without interference, but when lowered, as shown in Figs. 1, 2, 5, and 9, it is in an operative position with respect to the bolts and nuts to be tightened, and when in this position the rear horizontal flanges of the frame beams 20 rest upon the forwardly extending arms of the frame G.

Associated with the frame G are a pair of bent levers 37, that are carried on the ends of the shaft 32, and are connected at their forward ends to the beams 20, by short links 38. Upwardly extending arms of the levers 37 form sockets to removably receive the lower ends of a pair of bars 39, the upper ends of which are connected by a handle in the form of a cross bar 40. The bars 39 are also connected, at lower points, by a cross bar 41 that is releasably engageable with a hook or latch 42 carried upon a post 43, as shown in Fig. 4, and this connection when completed has the effect of holding the rear end of the machine in the raised position there shown, as will more fully presently appear.

The post 43 has a socket at its lower end to fit over the upwardly projecting end of a shaft 44, (Figs. 8 and 9), rotatably secured in the hub 36, and has a side slot which fits over a laterally projecting key 45, of the shaft 44, and, at its upper end has a hand wheel 46. When the hand wheel 46 is turned in either direction it will correspondingly oscillate the shaft 44, yet it is readily detachable with respect to the shaft, and can be quickly pulled off, as would be done when the machine is to be tumbled over; and of course would also be removed to render the machine more compact for purpose of shipping. The bars 39 can similarly be quickly removed from the members 37, and for the same reasons.

When the machine is in an operative or working position, as shown in Figs. 1 and 3, the frame 39-41 is in a forward, out-of-the-way position, so that the operator, standing at the rear, has free use of the wheel 46 and is also in an advantageous position to observe and control the work being done. When the machine is to be moved on the rails he then reaches forward, grasps the handle bar 40, and pulls the frame 39 back until the bar 41 snaps under the latch 42. This action, operates through the levers 37 and links 38, to raise the main frame 20 to the position shown in Fig. 4, but the frame G, operates on different centers (i. e., 32 and 34) and consequently the post 43 is tilted back to a lesser degree, as shown.

The function of the post 43 and hand wheel 46 is to control or effect a to and fro action as between the device for holding the bolt in place and the wrench which turns the nut on or

off the bolt. The rest of the mechanism for effecting this operation, and its operation, may be described as follows: A cast frame H is transversely movable with respect to the frame G, and has a pair of integral, rearwardly extending arms 47 that slidably engage the shaft 32, one at each side of the roller 31. In addition to the shaft 32 the frame H is slidably secured with respect to the frame G by a guide bar 48, secured in the frame G (see Figs. 1 and 9). The frame H has a transversely disposed toothed rack 49 that meshes with a spur pinion 50 carried at the lower end of the shaft 44. The cast frame H is further provided with a pair of forwardly extending, bifurcated arms 51, to which are pivotally secured, as at 52, a pair of keeper levers 53. These levers are provided, at their outer or swinging ends, with concave heads 53¹ for engagement with the bolt heads. Only one of these keepers is of course used at a time, as the nut wrench operates at the other side of the rail and consequently they may selectively be let down and raised, depending upon which one is required for use. The pivot ends of the keeper levers are provided with lug portions 54 which, when the head ends of the levers are dropped down, stop against shoulders 55 of the frame H so that the heads 53¹ will not drop below the level of the bolt heads.

The nut wrenches 56, later to be described, and of which there are two, one at each side of the rail, are not transversely movable with respect to the main frame of the machine, but are applied to and removed from the nuts by a transverse shifting of the entire rear end of the machine which swings from the point of contact between the front roller support 25 and the rail. This shifting is effected in conjunction with the application of the keeper levers 53 to the bolt heads, as follows: When a bolt is to be tightened, released, or removed, the machine is first moved to the proper position on the rail, and is then lowered with the wrenches in the neutral or inactive positions as shown in Fig. 5. If the head of the bolt is at the left then the left hand keeper lever 53 is dropped down. The hand wheel 46 is now turned to the left or in an anti-clockwise direction, which action, operating through the rack 49 and pinion 50, causes the frames G and H to effect engagements at the opposite ends of the bolt. Thus the head 53¹ is pressed in a right hand direction against the bolt head; and the frame G, carrying the main frame 20 with it, moves to the left, the shaft 32 sliding through the roller 31 and arms 47, until the right hand wrench 56 is brought into complete engagement with the nut F². In a similar manner a bolt with its head at the right may be operated on by employing the right hand keeper 53 and the left hand wrench 56, in which event the hand wheel 46 would be turned to the right, but in either event it

will be noted that the opposed pressures, by the keeper and wrench in use, are equalized and are readily applied and removed. When the work on a bolt is completed the main frame should be restored to the central or inactive position before moved on to the next bolt.

As shown particularly in Figs. 5, 8, and 9, the wrenches have enlarged socket forming heads for engagement with the nuts, and these heads are carried on shanks 57 that are rotatably secured in depending legs or portions 58 of the housing 23. The wrench shanks are releasably secured by pivoted latch members 59 (see Figs. 1, 4, and 8) adapted to slip into annular grooves in the outer ends of the shanks. The shanks 57 are provided, intermediate their ends, with squared sections 60, adapted to fit in and be driven by respective pinions 61 and 62. The pinion 61 (Figs. 5 and 6) operates in the lower end of the right housing leg 58, and is the lowest of a train of four pinions, 61, 63, 64, and 65, the last of which is keyed on a transversely disposed shaft 66. The pinion 62, operating the opposite wrench 56, is driven by the shaft 66, through but two pinions 67 and 68. Thus, the direction of rotation of the wrenches is reversed, so that with the shaft 66 turning in a predetermined direction both wrenches will be rotating in either right hand or left hand directions with respect to the nuts with which they are respectively engageable. It may here be noted that with possibly slight modifications in the machine the wrenches 56 may be substituted by drills, reamers, and other tools, and to that extent I anticipate a broader use of the machine than solely for the purpose of operating on bolts and nuts, and I therefore do not herein confine myself to such limited use.

The shaft 66 is driven by a worm gear 69, on one end of the shaft, that is suitably housed in a portion of the casing 23. This gear meshes with and is in turn driven by a worm 70 on the rear end of a suitably journaled shaft 71, said worm being housed within a casing 72 secured on the housing 23.

The shaft 71 is preferably journaled in roller bearings 73 and 74, (see Fig. 10), and in a bearing head 75, extending up from the main frame 20. At its forward end the shaft 71 has a sprocket pinion 76, that is keyed thereto, and is driven by a sprocket chain 77 (see Fig. 11) from a sprocket gear 78, secured on a clutch member 79. Rotatable on an intermediate portion of the shaft 71 is a sprocket gear 80 having chain drive connection with a sprocket pinion 81 of a clutch member 82. The gear 80 is rendered rotatable with or on the shaft 71 by a slideable clutch member 83 that is keyed to the shaft 71 and is reciprocated by a shifter lever 84 having a bifurcated end or fork that operates between a collar 85 fixed on

the member 83 and a collar 86 that is spring held against the shipper by a spring 87. Thus when the shipper 84 is moved forward (i. e., to the right as seen in Fig. 10) it will positively disengage the complementing clutch teeth 88; and when moved rearwardly will reengage the clutch although the spring 87 will permit the shipper to move rearwardly even if the clutch teeth 88 do not immediately engage each other. The shipper lever 84 is trunnioned on a shaft 89 that has limited reciprocating and oscillating movements in bearings 90. In a center opening of the shipper 84 is an opening in which a collar 91 is located and is rigid with the shaft 89. Thus, when the shaft 89 is moved back and forth it will correspondingly actuate the shipper, but the latter will in no way be influenced by oscillations of the shaft 89 and collar 91.

The shipper 84 is provided with a second fork 92 operating in a groove 93 between two inner integrally formed clutch members 94 and 95, that respectively co-operate with the outer clutch members 79 and 82. The clutch hub 94—95 is slidably keyed upon a power shaft 96 upon which the clutch members 79 and 82 are rotatable. It will thus be seen that when the shipper 84 is moved forwardly, and the power shaft 96 is running, the clutch members 79 and 94 will be closed thus causing the gear 78 to drive the pinion 76 and shaft 71 at a relatively high speed. When a lower speed is desired the shipper 84 is pulled backward, to disengage the clutch 79—94, and this movement effects a closing of the two clutches 88 and 82—95. The relatively small pinion 81 then causes a slower action or motion of the gear 80 and shaft 71.

The rear end of the shaft 89 is pivotally secured, as at 97, to a head lever 98 mounted in a bracket 99 having a T-shaped slot 100. The lower end of the lever 98 is slidably supported in a transverse channel portion 101 of the bracket 99. When the hand lever 98 is now pulled back, to the rear end of the notch 100, it operates through the shipper lever 84 to complete the low speed drive connection between the shafts 96 and 71, and, to effect the high speed drive connection it is only necessary to push the hand lever 98 to its extreme forward position. In this manner the shaft 96, driven by the engine in a manner presently to be described, imparts a right hand or screwing on rotation to the wrenches 56 after one of them has of course first been applied to a nut. The degree of pressure or power required to properly screw home a nut is of course very high, and consequently the operating wrench has a very tight rotatable contact with the fully secured nut; in fact this contact or grip is so great that the wrench cannot be removed from the nut until it has first been

released by a slight back or left hand action of the wrench. Merely releasing the power is not sufficient to release the wrench, due to the locking action of the worm 70 on the gear 69. To overcome this difficulty I provide the collar 91, that is rigid on the shaft 89, with a forked arm 102 (see Figs. 11 and 12) that engages a small plate 103 on the upper end of an inclined squared shaft 104 slidably secured in an inclined, rigid post or standard 105. At its upper end the shaft 104 carries a truncoconical disk 106, which when lifted is adapted to frictionally connect a pair of friction flanges 107 and 108 on the respective clutch members 95 and 79. The clutch disk 106 is pressed into engagement with the flanges 107 and 108 by a slight rock or partial rotation of the shaft 89, and this is done by moving the hand lever 98 from its neutral position to the left in the transverse portion of the slot 100. It will now be seen that the power or motion of the power shaft 96 is reversed to the shaft 71, being transmitted successively through the elements 95, 107, 106, 108, 79, 78, 77, and 76. The leftward shift of the hand lever 98 is of course only momentary, and as soon as it is seen that the wrench is loose the lever is returned thus dropping the disk 106 out of engagement with the flanges 107 and 108.

The power transmitting mechanism also includes a device for automatically releasing the power to the wrenches when such power reaches a predetermined degree, thus insuring a uniformity of clamping pressure by each bolt, and preventing an overstrain on or unintentional twisting of the bolt. This device also includes means for optionally rendering it inactive so that a greater than normal amount of power may be applied to the wrenches, as may be desired for instance when a nut is rusted or "frozen" on the bolt. This device is illustrated particularly in Figs. 13-17, and may be described as follows:

The forward end of the shaft 96 terminates and rotates in the hub 109 of the fly wheel 110 of the engine or power unit 111. A short inner hub 112 is keyed to the shaft 96, while a larger outer hub or annular housing 113 is rigidly secured, as by bolts 114, to the fly wheel 110. The hubs 112 and 113 are connected by a relatively heavy spring 115 that is always under tension and through which power is transmitted from the engine to the shaft 96. A sleeve 116 extends between the shaft 96 and the hub 113, and has an enlarged end or disk portion 117 that engages against the end of the hub 113. This disk 117 is provided with peripheral notches 118, to which a spanner wrench may be applied to turn it, and the disk is releasably locked, with respect to the hub 113 by a pin 119 that may be inserted in any one of a series of annular perforations 120 in the end of the hub 113. The

inner periphery of the member 116—117 is provided with a pair of opposed, segmental slots 121, in which operate integral splines or keys 122 of the shaft 96, said keys being considerably narrower than the slots so as to have freedom for limited oscillating movement therein, the object of which will presently be set forth.

At its outer end the member 116 is provided with a cam face 123 which engages a similar cam face 124 of a hub 125 that is slidably but non-rotatably keyed on the splines 122 of the shaft 96. A ring 126, preferably consisting of a pair of semi-circular segments, is inset in notches in the keys 122, so as to hold the sleeve 116 against outward movement, and consequently if the sleeve 116 turns with respect to the hub 125, within the limits permitted by the keys 122 in the slots 121, the cam face 123 will push the hub 125 outwardly. This outward movement is in turn imparted to a collar 127 that is rotatable with respect to the hub 125 and is pivotally secured, as at 128, to one arm of a lever 129, in turn fulcrumed to a stationary support 130. The opposite arm of the lever 129 is forked, to engage the forward end of the shaft 89, which shaft end is provided with an adjustable stop nut 131. A latch 132 is pivoted to the lever 129 and when dropped down, as shown in Figs. 13 and 17, lessens the space or freedom of movement between the lever 129 and the nut 131. This space, between the latch 132 and nut 131, is sufficiently large to permit the normal shifting of the shaft 89 to throw the machine into either high or low clutch connections. During the normal nut screwing operation power is transmitted from the engine to the shaft 96 through the elements 109, 110, 114, 113, 115, and 112, the spring 115 being sufficiently strong and tightened to transmit the load without permitting the slots 121 of the sleeve 116 to advance on the keys 122. But when the nut is firmly screwed on it reacts through the gears and clutches previously described, to set up a resistance against the spring 115, through the hub 112, and as this resistance increases it causes the sleeve 116 to turn on, and momentarily not with, the shaft 96, within the limit of movement of the keys 122 in the slots 121, and when this limit is reached there has been a sufficient rotation of the sleeve 116 with respect to the hub 125 to bring the cam faces 123 and 124 into action, and this reacts on the lever 129, causing the latch 132 to engage the nut 131 and move the clutch operating shaft 89 forward to its neutral position, it being understood that it would previously have been operating in its rear or low speed position. To change the degree of resistance required to set the automatic release mechanism in action it is only necessary to remove the pin 119 and turn the sleeve 116 with respect to the hub 113, thus tightening or loosening the spring

115 after which the pin 119 is replaced. This is in effect adjusting the shaft 96 with respect to the fly wheel 110, and while any convenient method for doing so may be used, I prefer to apply a spanner wrench to the notches 118 while the fly wheel is held against rotation.

When it is desired to apply positive and checked power to the wrenches, as for instance when a nut is rusted or "frozen" on, it is only necessary to raise and throw back the latch 132. By so doing the clearance between the lever 129 and nut 131 is enlarged to the point where the cam action 123—124 will not be sufficiently great to take up the additional clearance to move the shaft 89.

To unscrew or remove a nut it is necessary to reverse the engine, or, if desired, provide a reversing mechanism between the engine and hub 109. In either event there is no necessity for utilizing the automatic release mechanism, above described. In fact it cannot be used at all, because if a nut cannot be removed with a predetermined degree of pressure the pressure must be increased until, if necessary, it forcefully twists off the bolt. But the power transmitting mechanism is without any adjustment, in readiness to accommodate this condition. With the hub 113 rotating in the opposite direction (from that indicated by the arrows in Fig. 15) the sleeve 116 positively engages the keys 122 of the shaft 96, and consequently the spring 115 plays no part in transmitting the power.

It is understood that suitable modifications may be made in the general design and structural details of the machine as herein shown and described, provided, however, that such modifications come within the spirit and scope of the appended claims.

Having now therefore fully shown and described my invention, what I claim is:

1. A machine of the character described comprising a frame adapted to be supported and travel on a pair of rails, and with its center of gravity substantially above one of the rails whereby the entire machine may be quickly tumbled off the rails, and longitudinally spaced rockers for supporting the machine when tumbled from the rails.

2. A machine of the character described, comprising a portable frame adapted to be supported at its front and rear ends upon a rail and with the center of gravity of the machine substantially above the rail, laterally extending means for normally retaining the machine in an upright position, a track working tool and power unit carried by the frame, and rockers carried by the frame for supporting the machine when tumbled from its normal upright position.

3. A bolt tightening machine for rails, comprising a frame having wheel supports at its ends for supporting engagement with a rail, means for transversely shifting one end of the frame with respect to its wheel

support, a bolt retaining member and a nut engaging member carried at said end of the machine, one of said members being movable with respect to the rail and the other stationary with respect to the rail when said end of the frame is shifted.

4. A bolt tightening machine for rails, comprising a frame having wheel supports at its ends for supporting engagement with a rail, means for transversely shifting one end of the frame with respect to its wheel support, a bolt retaining member and a nut engaging member carried at said end of the machine, one of said members being movable with respect to the rail and the other stationary with respect to the rail when said end of the frame is shifted, and means for vertically adjusting said end of the frame into and out of working position with respect to the rail.

5. In a machine of the character described, a pair of transversely aligned nut tightening wrenches, and a pair of bolt engaging holding devices adapted each to be employed with the oppositely disposed wrench, said holding devices each being mounted for adjustable movement in a plane extending at right angles to the axis of the bolt to be held by it.

6. In a machine of the character described, a pair of transversely aligned nut tightening wrenches, means for simultaneously raising and lowering the wrenches, and means transversely movable with respect to and between the wrenches for engaging the head of the bolt of which its nut is engaged by one of the wrenches.

7. A bolt tightener for a rail comprising a machine movable on the rail and having a pair of power operated wrenches, one disposed at each side of the rail, for selective engagement with nuts of reversely arranged rail bolts, and holding members for engaging and retaining the bolt when the nut thereof is being turned by one of the wrenches, said holding members being liftable from the bolt engaging position in a plane extending parallel with the track.

8. In a machine of the character described, a power driven shaft, a rail tool adapted to be driven thereby, and a power transmission device for transmitting power from the shaft to the tool including means for automatically disengaging the power when the resistance of the tool reaches a predetermined degree, and means for rendering said disengaging means inoperative when it is desired to apply a positive force to the tool irrespective of the resistance thereof.

9. In a machine for operating on bolt nuts, a wrench for engaging the nut to tighten it on the bolt, a power unit, a clutch controlled power device for transmitting power from the unit to the wrench, said power device having a quick acting power reversing means

whereby the wrench may be loosened from the nut.

10. A machine for working on rail tracks comprising a frame to be carried on a track, a motor and track working mechanism carried on the frame, and rockers secured to the frame and extending therefrom to protect said motor and mechanism when the machine is tumbled from the track.

11. A rail working machine comprising a main frame for supporting a rail working mechanism and having a support at its front end for engagement with the rail, a secondary frame for supporting the rear end of the main frame, a roller mounted rearwardly in the secondary frame for supporting both frames, the front end of the secondary frame being pivotally connected to the main frame, a hand lever fulcrumed to the secondary frame, and a lifting link connecting the hand lever to the main frame.

12. A rail working machine comprising a main frame for supporting a rail working mechanism and having a support at its front end for engagement with the rail, a secondary frame for supporting the rear end of the main frame, a roller mounted rearwardly in the secondary frame for supporting both frames, the front end of the secondary frame being pivotally connected to the main frame, a hand lever fulcrumed to the secondary frame, and a lifting link connecting the hand lever to the main frame at a point rearwardly of the pivot connection between the two frames.

13. A rail working machine comprising a main frame for supporting a rail working mechanism and having a support at its front end for engagement with the rail, a secondary frame for supporting the rear end of the main frame, a roller mounted rearwardly in the secondary frame for supporting both frames, the front end of the secondary frame being pivotally connected to the main frame, a hand lever fulcrumed to the secondary frame, and a lifting link connecting the hand lever to the main frame, said secondary frame serving as a support for the rear end of the main frame when the latter is in its lowered or operative position with respect to the rail.

14. A rail working machine comprising a main frame for supporting a rail working mechanism and having a support at its front end for engagement with the rail, a roller for supporting the rear end of the main frame, and means for transversely shifting the rear end of the main frame with respect to the roller so as to adjust the rail working mechanism laterally with respect to the rail.

15. A rail working machine comprising a main frame for supporting a rail working mechanism and having a support at its front end for engagement with the rail, a roller for rail engagement at the rear end of the

main frame, a shaft slideable axially in the roller, an adjustable supporting connection between the shaft and main frame, and means for adjusting the shaft longitudinally in the roller.

16. A rail working machine comprising a main frame for supporting a rail working mechanism and having a support at its front end for engagement with the rail, a roller for supporting the rear end of the main frame, and means for vertically and transversely adjusting the main frame with respect to the roller.

17. A rail working machine comprising a main frame for supporting a rail working mechanism and having a support at its front end for engagement with the rail, a roller for supporting the rear end of the main frame, a secondary frame connecting the main frame to the roller, and transversely adjustable with respect to the roller to correspondingly adjust the main frame.

18. A rail working machine comprising a main frame for supporting a rail working mechanism and having a support at its front end for engagement with the rail, a roller for supporting the rear end of the main frame, a secondary frame connecting the main frame to the roller, and transversely adjustable with respect to the roller to correspondingly adjust the main frame and a third frame transversely movable with respect to the second frame but held against transverse movement with respect to the roller to serve as a tool member support in conjunction with the rail working mechanism of the main frame.

19. A rail working machine comprising a main frame for supporting a rail working mechanism and having a support at its front end for engagement with the rail, a roller for supporting the rear end of the main frame, a secondary frame connecting the main frame to the roller, and transversely adjustable with respect to the roller to correspondingly adjust the main frame and a third frame movable with respect to the secondary frame but held against movement with respect to the roller, and manually operative means for transversely shifting the secondary and third frames with respect to each other.

20. A railway bolt tightening machine comprising a main frame having a wrench adapted to engage the nut of a rail bolt, a roller for supporting part of the frame, means for transversely shifting the frame with respect to the roller so as to engage or disengage the wrench with respect to the nut, and means for engaging the bolt when the nut wrench is operated.

21. A railway bolt tightening machine comprising a main frame having a wrench adapted to engage the nut of a rail bolt, a roller for supporting part of the frame,

means for transversely shifting the frame with respect to the roller so as to engage or disengage the wrench with respect to the nut, and a bolt engaging member associated with the roller so as to be held against transverse movement when the main frame is shifted.

22. A bolt tightener comprising a power unit, a wrench, a power transmission device including high and low speed connections for transmitting power from the unit to the wrench, and means for disengaging the low speed connection when the resistance to the wrench reaches a predetermined degree.

23. A bolt tightener comprising a power unit, a wrench, a power transmission device including high and low speed connections for transmitting power from the unit to the wrench, and quick acting power reversing means for loosening the wrench from the nut.

Signed this 28th day of January, 1929, at Minneapolis, Minnesota.

HORACE E. WOOLERY.
